DESIGN FOR A VEILING OR SIMILAR ARTICLE

Louis Young, New York, N. Y., assignor to Young's Textile Mills, Inc., New York, N. Y., a corporation of New York

Application March 21, 1941, Serial No. 99,764

Term of patent 3½ years

To all whom it may concern:

Be it known that I, Louis Young, a citizen of the United States, residing at Bronx, New York city, in the county of New York and State of New York, have invented a new, original, and ornamental Design for a Veiling or Similar Article, of which the following is a specification, reference being had to the accompanying drawing, forming part thereof.

The figure is a plan view of a piece of veiling,
showing my new design.

I claim:

The ornamental design for a veiling or similar article, as shown.

LOUIS YOUNG.
